(57) **CLAIM**

The ornamental design for a bracket with anchor screw, as shown and described.

DESCRIPTION

FIG. 1 is a front top right side perspective view for a bracket with anchor screw, showing my new design;

FIG. 2 is a rear bottom left side perspective view of FIG. 1 thereof;

FIG. 3 is a front elevational view of FIG. 1 thereof;

FIG. 4 is a rear elevational view of FIG. 1 thereof;

FIG. 5 is a left side elevational view of FIG. 1 thereof;

FIG. 6 is a right side elevational view of FIG. 1 thereof;

FIG. 7 is a top plan view of FIG. 1 thereof; and

FIG. 8 is a bottom plan view of FIG. 1 thereof; and,

FIG. 9 is an exploded front top right side perspective view of the bracket with anchor screw of FIG. 1 thereof showing the bracket and anchor screw separated.
